LONG DRAFT DRAWING ROLL

William Beswick, Birmingham, Ala.

Application January 2, 1943, Serial No. 471,104

7 Claims. (Cl. 19—130)

My invention relates to drawing apparatus for attenuating machines in textile mills, such as the drawing, slubbing, intermediate and spinning frames, and has for an object the provision of apparatus of the character designated which shall be simple of design and operation, and capable of effecting an even drawing of the roving with a greater ratio of speed between the front and rear rolls than has heretofore been the practice.

In my previously filed application, Serial No. 457,277, filed September 4, 1942, there is shown, described, and claimed an attenuating apparatus in which a plurality of single drawing rolls are caused to cooperate with closely adjacent concentric troughs, with ridges between the adjacent troughs, over which the roving is drawn and in which the proper pressure between the rolls and the troughs may be obtained by adjusting the troughs with relation to their cooperating rolls. It is the principal object of this invention to obtain all the benefits of the invention of my application aforesaid, without the possibility of hanging, bunching, or snarling of the fiber.

In accordance with my present invention, I employ the single drawing rolls, and, in addition to the concentric troughs, I provide relatively small, light weight rolls which cooperate with the troughs and the drawing rolls to effect an even travel of the roving through the apparatus without bunching or snarling. The small rolls do not interfere with the drawing operation effected by the single drawing rolls and troughs. In one form of my invention I may dispense with the concentric troughs and substitute therefor a plurality of relatively small rolls which cooperate with each drawing roll in a manner to cause the roving to be continuously drawn, as with the concentric troughs. In all embodiments of my invention the rolls may be spaced closely adjacent, or much closer than the length of staple or fiber from which the yarn is being spun, and the fibers are evenly drawn by the single drawing rolls, none being drawn out of turn.

Apparatus embodying features of my invention is illustrated in the accompanying drawings forming a part of this application in which

Fig. 1 is a front elevational view showing one form of my invention, with certain parts removed;

Fig. 2 is an end elevational view of the same;

Fig. 3 is a sectional view taken along the line III—III of Fig. 1;

Fig. 4 is a view similar to Fig. 3 showing a modified form of my invention;

Fig. 5 is a detailed sectional view showing means for applying a slight pressure to the bottom rolls shown in Fig. 4; and

Fig. 6 is a sectional view similar to Fig. 3 showing a further modified form of my invention.

Referring to the drawings, I show roll stands 10 and 11 in which the rolls are supported. Mounted on the roll stands are front bearing supports 13 and 14 and rear bearing supports 16. Between the bearing supports 14 and 16 are intermediate supports 17, 18, and 19. All of the bearing supports are adjustably mounted on the roll stands and are slideable with respect to each other. When in adjusted position they are held in place by means of bolts 21 and 22 which pass through the bearing supports and into the roll stands. Mounted in the bearing support 14 is a lower metal fluted roll 23. Cooperating with the roll 23 is an upper covered roll 24. At the rear, in bearing support 16, there is mounted a lower metal fluted roll 26. Cooperating with the roll 26 is a covered roll 27. The rolls 24 and 27 are preferably weighted as by means of a saddle 28, bridle 29, and weighted lever 31.

Interposed between the front and rear roll assemblies just described are intermediate drawing rolls 32, 33, and 34 which are mounted in the bearing supports 17, 18, and 19, respectively. These rolls are preferably fluted metal rolls, though it will be understood my invention is not to be limited to any particular type of drawing roll. Mounted over the drawing rolls 32, 33, and 34, and extending from end to end of the entire assembly is a plate 36 having formed therein concentric troughs 37, 38, and 39 with which the rolls 32, 33, and 34, respectively, cooperate. The plate 36 is supported from front and rear bearing supports 13, 14, and 16 as shown in Fig. 2 by means of angles 41 and 42 secured to the bearing supports. Adjusting screws 43 extend through the angles into the plate 36 whereby its position may be adjusted vertically with respect to the rolls 32, 33, and 34. The plate 36 may be made of any suitable material capable of being accurately shaped as described. For example, it may be pressed metal or molded plastic or glass.

It will be noted that each of the troughs 37, 38, and 39 defines, in cross section, slightly less than a semi-circle, so that the centers of the rolls 32, 33, and 34 are below the sides of the troughs. It will further be noted, by reference to Fig. 3, that there is a considerable space between the back rolls 26 and 27 and the first intermediate roll 34, the plate 36 defining a flat surface between said rolls under which the roving is drawn.

This spacing is to provide for a break draft, or slight loosening of the twist in the roving, and is preferably made slightly greater than the average length of staple or fiber being spun. A suitable opening is provided in the plate 36 for the passage of the bridle 29. It will further be noted by reference to Fig. 3 that the troughs 37, 38, and 39 define between them ridges 44 and 46 under which the roving is drawn, and it is contemplated, in accordance with my invention, that the principal part of the drawing takes place as the roving is passing under said ridges.

Mounted over the intermediate rolls 32, 33, and 34, respectively, are relatively small metal rolls 47, 48, and 49. The rolls 47, 48, and 49 are mounted in adjustable bearings 51, 52, and 53 which are adjustably mounted on a rod 54, which in turn is adjustably mounted in a hinged support 55 at the back of the assembly. The small rolls 47, 48 and 49 protrude through suitable slots formed in the troughs 37, 38, and 39 to cooperate with the intermediate drawing rolls 32, 33, and 34. The small rolls are not weighted and bear only by their own weight on the fluted rolls 32, 33, and 34. The function of the small rolls is to prevent bunching or snarling of the fibers in the roving and to insure its continuous passage through the assembly.

The operation of the apparatus so far described is as follows:

The roving indicated by the letter R in Fig. 3 enters between the back rolls 26 and 27 through a trumpet 57. It passes under the flat surface of the plate 36 between the back rolls 26 and 27 and drawing roll 34 which, being a distance slightly greater than the length of the fibers in the roving, permits a break draft or slight loosening of the twist, and facilitates the further drawing of the roving. The roving then passes successively over the fluted rolls 34, 33, and 32, in the order named, and out between the front rolls 23 and 24. It will be understood that the rolls are driven at progressively increasing speeds from back to front, in a manner well understood, and which is not shown in the drawings. For example, the ratio of speed of the roll 34 to rolls 26 and 27 may be the usual break draft of 1.00 to 1.15 to 1.25. The ratio of speed of rolls 34 and 33 may be 1.00 to 3.00 to 4.00; and the ratio of the speed of rolls 32 to 33 may be 1.00 to 5.00 to 6.00. The ratio of the speed of the front pair of rolls 23 and 24 to the roll 32 should be only enough to maintain tension in the roving, as the drawing has already been completed by the time the roving leaves the intermediate roll 32. It will be seen that by means of my invention, the roving is in engagement with each of the fluted intermediate rolls for a distance equal to one-half the circumference of the roll and a partial drawing may occur for the entire distance the roving is in engagement with a roll. It appears, however, that the principal part of the drawing takes place as the roving is passing under the ridges 44 and 46. Placing the centers of the rolls 32, 33, and 34 below the ridges 44 and 46 provides for easier threading of the roving through the rolls, while the relatively small rolls 47, 48, and 49 prevent any bunching or snarling of the fibers in the roving in the troughs.

Referring to Fig. 4, I show a modified form of my invention. In this modification the front rolls 23 and 24 and the back rolls 26 and 27 are mounted the same as hereinbefore described and

require no further description. In accordance with this modification, I also provide the intermediate fluted rolls 32, 33, and 34, but instead of the plate 36 being mounted over the intermediate rolls, I provide a plate 58 having formed therein concentric troughs 59, 60, and 61 which cooperate with the intermediate rolls 32, 33, and 34, respectively, and are disposed beneath said rolls. Ridges 62 and 63 between the troughs 59 and 60, and 60 and 61, respectively, correspond to the ridges 44 and 46 in Fig. 3, and provide a surface over which the roving is drawn by the intermediate rolls. It will be noted that the ridges 62 and 63 extend to a plane slightly below the plane joining the centers of the intermediate rolls 32, 33, and 34, thereby providing for the easy threading of the roving through the rolls.

In accordance with this modification, I mount relatively small rolls 65, 64, and 66 beneath the plate 58, which rolls project through suitable longitudinal slots formed in the plate to cooperate with the intermediate rolls 32, 33, and 34, and prevent bunching and snarling of the fibers in the roving as it is being drawn. In order to overcome the force of gravity and provide slight pressure on the small rolls 65, 64, and 66, I mount beneath each of said rolls one or more springs 67 each of which bears at its lower end against a plate 68 beneath the rolls, and carries on its upper end a bearing 69 which bears against the neck 71 of its associated roll to exert upward pressure against the roll and hold it in engagement with its associated intermediate roll. Only enough pressure is exerted by the spring 67 to insure sufficient pressure on the roving to prevent its bunching and snarling. In order to prevent displacement of the spring 67 I provide a cup shaped holder 72, at the lower end, which is secured to the plate 68, and a cup shaped holder 40 73, at the upper end, which is secured to the bearing 69.

In Fig. 6 I show a still further modified form of my invention. In accordance with this modification, instead of the concentric troughs and small rolls cooperating with the intermediate rolls as hereinbefore described, I provide a plurality of much smaller rolls to cooperate with each of the intermediate rolls, thus providing a plurality of points of engagement for the roving with each of the drawing rolls. For example, I show three small rolls 74, 76, and 77 cooperating with intermediate roll 32; three small rolls 78, 79, and 81 cooperating with intermediate roll 33 and three small rolls 82, 83, and 84 cooperating with intermediate roll 34. It is contemplated that in accordance with this modification, the center roll of each group, that is rolls 76, 79, and 83, will be mounted in a bearing similar to bearings 51, 52, and 53 shown in Fig. 2, and that the companion rolls in each group will be linked to the middle roll as shown in Fig. 6. It will be obvious that, if desired, each of said rolls may be mounted in an independent bearing. In accordance with this modification, a slight pressure is necessary on rolls 77 and 81, upon which the heaviest duty is imposed, to prevent lifting of said rolls too high responsive to the drawing action on the roving by the rolls 32, 33, and 34. I therefore mount a saddle 86 over said rolls and employ a spring, such as the leaf spring 87, secured at one end to the saddle 28, to exert a slight downward pressure on the saddle 86 and the rolls 77 and 81.

The operation of the modifications described is substantially the same as that described in

connection with Figs. 1 to 3, inclusive. The relative speeds of the rolls are the same as heretofore described and the drawing action is substantially the same. In all modifications, it will be seen that I provide a maximum area of engagement of the drawing rolls with the roving.

While I have shown my invention in several forms, it will be obvious to those skilled in the art that it is not so limited, but is susceptible of various other changes and modifications, without departing from the spirit thereof, and I desire, therefore, that only such limitations shall be placed thereupon as are specifically set forth in the appended claims.

What I claim is:

1. In apparatus of the character described, a plurality of rolls driven at progressively increasing speeds, concentric troughs disposed in closely spaced relation to the rolls, means forming ridges between the troughs extending substantially to a plane passing the center of the rolls, means to pass roving progressively over the ridges and between the troughs and the rolls, and a plurality of relatively small rolls associated with the troughs, each being mounted to project through the bottom of a trough to cooperate with the associated first mentioned roll and prevent bunching or snarling of the roving.

2. In apparatus of the character described, a fluted roll, a trough in which a substantial portion of the roll rotates and disposed in spaced relation with respect to the roll, said trough having an elongated slot in the bottom thereof, means to pass roving transversely of and between the roll and the trough, and a relatively small roll disposed to project through the slot and bear against the roving with sufficient pressure only to insure its even movement in the direction of rotation of the fluted roll without bunching or snarling.

3. In apparatus of the character described, a series of fluted rolls driven at progressively increasing speeds, a series of troughs in which substantial portions of the rolls rotate, and disposed in closely spaced relation with respect to the rolls, each of said troughs having an elongated slot in the bottom thereof, means to pass roving transversely of the rolls between the rolls and the troughs, and a series of relatively small rolls associated with the troughs, each of said small

rolls being mounted to project through a slot and bear against the roving with sufficient pressure only to insure its even movement in the direction of rotation of the fluted roll without bunching or snarling.

4. In apparatus of the character described, a series of fluted rolls driven at progressively increasing speeds, a plate spanning the rolls and adjustably mounted with respect thereto, a series of troughs formed in the plate and fitting about the rolls, a substantial portion of each of the rolls extending into its associated trough, each of said troughs having an elongated slot in the bottom thereof, means to pass roving progressively through the apparatus between the rolls and the troughs, and a series of relatively small rolls mounted to project through the slots and bear against the fluted rolls with sufficient pressure only to insure even movement of the roving

10 15 20 in the direction of rotation of the fluted rolls without bunching or snarling.

5. In apparatus of the character described, a series of fluted rolls driven at progressively increasing speeds, a plate spanning the rolls and formed to provide a series of troughs cooperating with the rolls with ridges intervening between the troughs, a substantial portion of each of said rolls extending into its associated trough, each of said troughs having an elongated slot in the bottom thereof, means to pass roving through the apparatus between the rolls and the troughs and across the ridges, and a series of relatively small rolls associated with the troughs and mounted to project through the slots and bear 30 35 against the roving with sufficient pressure only to insure its even movement in the direction of rotation of the fluted roll without bunching or snarling.

6. Apparatus as defined in claim 5 in which the plate member is mounted over the fluted rolls and the relatively small roll bears its own weight on the roving.

7. Apparatus as defined in claim 5 in which the plate member is mounted beneath the fluted rolls and each of the relatively small rolls is mounted to project upwardly through the slot in its associated trough, and spring means for exerting pressure on each of the relatively small rolls.

WILLIAM BESWICK.
